TELEPHONE DIAL MARKINGS

Russell A. Chapin, Santa Monica, Calif.

Application September 19, 1942, Serial No. 458,963

2 Claims. (Cl. 179—90)

My invention relates more particularly to markings on the manually operated dials of the automatic telephone, and has among its salient objects: to provide an improvement in the markings on the dial which will make it possible to accurately dial a number when the light is poor, or even in the dark, and this is accomplished by marking, or distinguishing certain of the finger openings in the dial so that by the sense of touch, or by a more pronounced color, these openings will always be easily located, either by sight or by touch, and from these it is very easy to locate the other openings of any particular number which it is desired to dial. For example, if the openings for the numerals 4 and 7 are distinguished or differentiated from the other numbers, the numbers 1, 2 and 3 at one side, or 5 and 6 at the other side of the 4, can be quickly and easily located either by touch, or, if the light is dim, by the differentiating color, as it is preferable that these particular locations be differentiated by being raised and also by the use of a distinguishing color, as white on black.

Sometimes the position of the dial is so positioned that the operator cannot get a straight view thereof, but must see the dial at an angle, whereby the numbers cannot be seen with clearness, but with the differentiated openings, it is easy, with a little practice, to operate the correct numbers even though they are not clearly visible to the user.

I have found by actual experimentation, that more accurate dialing and faster dialing can be accomplished with my improved markings or dial differentiations than can be done with the present dial when the position of the dial is not convenient, or when the light is dim, and that a blind person can accurately dial a number with my improved markings as soon as he has become acquainted with the differentiating features.

In order to more fully explain my invention, I have illustrated the same on the accompanying sheet of drawings, which I will now describe:

Figure 1 is a plan view of a telephone dial embodying my invention, certain finger openings being differentiated by a coat of white enamel paint, and also with two bar-like strips painted in the blank space thereon;

Figure 2 is a fragmentary sectional view taken on line 2—2 of Fig. 1;

Figure 3 is a plan view of another embodiment of my invention in which the dial openings are differentiated by overlying metal portions, instead of the painted differentiation;

Figure 4 is a sectional view taken on line 4—4 of Fig. 3; and

Figure 5 is a fragmentary sectional view taken on the line 5—5, of Fig. 3.

5 Referring now to the drawing more in detail, I have shown in plan view the usual dial of the automatic telephone without the usual numerals or indicia thereon, showing only the differentiation features constituting my invention. The dial 10 to be manipulated in all the views is designated 7, with the usual finger openings 8 therethrough, and under which the usual numeral card is placed when that is to be used.

Referring now to Figs. 1 and 2, I have shown 15 painted on the dial, as with white enamel paint, over the openings which would normally be over the numerals 4 and 7, a tapering area for each, designated 9 and 10, respectively. These differentiate these particular openings 4 and 7 in the 20 color contrast, so as to be seen when the light is dim, but also, the coat of enamel paint would be slightly raised and could be felt with the fingers as they are moved over the dial, thus 25 making it easy to locate the particular dial openings for the numerals 4 and 7, by sight even when the light is poor, or by touch because the coat of enamel paint is raised over this area around these particular openings. On this dial I have also painted two bar-like strips, as 11 and 12.

30 These bar-like strips extend across the opposite side of the dial, in the area between the first and last finger openings in the dial, and at opposite sides of the stop element 13, on most phone dial mechanisms. The painted areas for the finger 35 openings 4 and 7, and also the bar-like strips 11 and 12, extend, preferably across the dial proper and up a short distance on to the center cap name plate, as indicated in the drawing.

By thus being able to locate the particular dial 40 numeral positions 4 and 7, it is a very easy thing to quickly, by touch, locate any of the related numerals, 1, 2 and 3, on one side of the 4, 5 and 6 on the other side thereof, of the 7, also differentiated and then the 8, 9 and 0. The addition of 45 the bar-like strips 11 and 12, also facilitate the quick determination of the normal position of the dial before dialing a number.

In Fig. 3, I have shown the dial plate, designated 7 and with the finger openings 8 thereon, but instead of painting the differentiating area about the numeral positions 4 and 7, I have shown the center retaining cap member 14, as having formed as a part thereof two overlying extensions 15 and 16, to overlie the numeral 55 positions 4 and 7, respectively, and at the oppo-

site side, also having formed as a part thereof, the two bars 17 and 18, in the same positions that the painted bar-like strips 11 and 12 are, relative to the stop element 13. This annular cap or retaining ring 14 also has formed thereon the toe-like extensions 14' to be inserted down through openings in the dial 7 for holding it and the name or phone number card in place therein, in the center of the dial in the usual manner.

Other ways could be used to differentiate certain numeral positions, or finger openings, to make them easily located or known in poor light, or even in the dark by the sense of touch, and from which it is easy to quickly locate the particular numeral positions by the sense of touch from these differentiated locations, and I do not limit my invention to the specific means here shown for accomplishing that purpose, except as I may be limited by the hereto appended claims.

I claim:

1. A telephone dial having finger openings for manipulation, all in the same plane, and having an intermediate finger opening differentiated by 5 a raised area for location thereof by touch and from which to locate other finger openings for dialing purposes.
2. A telephone dial of the character shown and 10 described operable without numerals and letters and having finger openings for manipulation, some of said finger openings being differentiated to be located by the sense of touch, the differentiating means being a raised surface around said opening, and other raised means associated with 15 the first and last openings of said dial for aid in locating the same by touch.

RUSSELL A. CHAPIN.
